UNILATERALIZED TRANSISTOR CIRCUITS

Ge Yao Chu, Ipswich, Mass., assignor, by mesne assignments, to Sylvania Electric Products Inc., Wilmington, Del., a corporation of Delaware

Application May 22, 1956, Serial No. 586,493

8 Claims. (Cl. 330—27)

The present invention relates generally to transistor amplifier circuits, and more particularly to circuits having inverse feedback to neutralize the inherent feedback in the transistor.

The characteristics of junction type transistor amplifiers, like those of triode vacuum tubes, vary with the frequency of the applied signal. Observation of the gain, stability (i.e., freedom from tendency to oscillate), selectivity and input impedance as functions of frequency reveals the existence of considerable internal feedback at frequencies appreciably above the audio range, for example, near or above the intermediate frequency of 455 kc. commonly employed for receivers for amplitude-modulated radio transmission. Ideally, an amplifier should be unilateral, that is, non-responsive to variations in the output signal, but the existence of inherent feedback leads to undesired bilateral characteristics. A primary object of this invention is to provide transistor amplifier circuits exhibiting unilateral properties and freedom from the effects of internal feedback.

Other collateral objects are to improve the input impedance characteristic, to render the gain more uniform within the band width of tuning, and to reduce or eliminate the tendency toward oscillation.

With the foregoing and other objects in view, the features of the invention comprise circuit means especially devised to apply external inverse feedback to the transistor amplifier, whereby the transistor becomes substantially non-responsive to its inherent feedback signal. There is thus provided a singly-tuned transistor amplifier of greatly improved characteristics for higher frequency applications. A further desirable result is that it is made possible to devise transistor amplifiers of variable band pass characteristics by the staggered tuning principle.

Other features reside in certain details of the circuits, and in modes of operation thereof which will become evident from the following description and from the appended drawings illustrating the same.

In the drawings,

Fig. 1 is a circuit diagram of an emitter-input transistor amplifier of conventional form;

Figs. 2 and 3 are equivalent circuit diagrams illustrating internal feedback in the circuit of Fig. 1 and its correction;

Fig. 4 is a circuit diagram of a first embodiment of the invention based on Fig. 3;

Figs. 5 and 6 are equivalent circuit diagrams illustrating a variation of internal feedback in the circuit of Fig. 1 and its correction;

Fig. 7 is a circuit diagram of a base-input transistor amplifier of conventional form;

Figs. 8 and 9 are equivalent circuit diagrams illustrating internal feedback in the circuit of Fig. 7 and its correction;

Fig. 10 is a circuit diagram of a third embodiment of the invention based on Fig. 9;

Fig. 11 is a diagram illustrating the characteristics of

an intermediate frequency amplifier according to the invention; and

Fig. 12 is a diagram illustrating the characteristics of an amplifier of conventional form as illustrated in Figs. 5 and 7.

Referring to Fig. 1, there is shown a grounded base transistor amplifier of conventional form and including an n-p-n transistor T of the junction type. An input signal e_1 is applied. The collector circuit includes a tuned tank circuit comprising an inductance L and a capacitance C_o . R_L represents an equivalent load which receives maximum power at the resonant frequency of the tank circuit. Conventional bias voltages are supplied by batteries E_1 and E_2 .

Ideally, such a circuit would have the characteristics exhibited in Fig. 11. Here, input resistance and reactance curves for the transistor alone are plotted against frequency (e_1 assumed constant in amplitude) and show no appreciable change adjacent or within the pass band, while the output voltage sharply increases in the pass band due to the change in reactance of the tank circuit. However, by observation it is found that the actual input impedance of the amplifier at a frequency of 455 kc. is typically as represented in Fig. 12. The resistance and reactance of the transistor undergo marked change within the pass band, and the illustrated resistance and reactance curves reflect these changes as well as those of the tank circuit itself. These impedance variations within the transistor are not only appreciable at frequencies substantially above the audio range, but also undesirable because they tend to reduce the gain and stability of the amplifier.

It is useful to describe the observed results in terms of a so-called "equivalent circuit." Within a degree of approximation and within a particular range of frequencies, this circuit may take the form shown in Fig. 2 in broken lines. The emitter circuit responds substantially as if it included an emitter resistance r_e in series with a base resistance r_b , the latter including a resistance r'_b . In like manner, the collector circuit responds as if it included an active current generator G and a collector capacitance C_e connected from one output terminal to the point of connection of the resistance r'_b with the other resistance making up r_b . The generator G is defined as a source of infinite internal impedance which carries a current αi_e , where α is the transfer current amplification factor of the transistor. From these assumptions it follows that the output voltage e_o influences the input current i_e , and by definition also the current output of the generator G. Since the resistance r'_b is in the input circuit, the feedback voltage e_f is the voltage across this resistor due to the output voltage e_o . This voltage has a substantial component in quadrature with the voltage e_o by reason of the capacitance C_e .

Thus

$$(1) \quad e_f = \frac{e_o r'_b}{r'_b + \frac{1}{j\omega C_e}}$$

To balance out or neutralize this component there is introduced an external feedback circuit to provide a balanced bridge as shown in Fig. 3. Here, the same equivalent circuit as that of Fig. 2 is shown as connected with external impedances R_b and C_o , the external impedances having such values that no voltage appears across the terminals of the input voltage e_1 in response to the voltage e_o . This condition is satisfied if a neutralizing voltage e_n equals the feedback voltage e_f , which leads readily to the expression

$$(2) \quad r'_b C_o = R_b C_o$$

This is the condition imposed on the impedances R_b

and C_o for a unilateral characteristic. It is seen that this is a function of the observed internal feedback characteristics of the transistor.

Replacing the equivalent circuit with the conventional symbol for the transistor and rearranging the impedances, we have the circuit of Fig. 4. This circuit is substantially unilateralized to the extent that the actual characteristics of the transistor are fairly represented by the given equivalent circuit of Fig. 2 and the assumed impedance values r'_b and C_e thereof.

Under certain conditions, the equivalent circuit for a transistor amplifier connected like that of Fig. 1 is more accurately represented by Fig. 5. Here, in addition to the impedances C_e and r'_b , there is shown a collector resistance r_c in parallel with the active current generator G . The resistance r_c , by absorbing a portion of the current $a_i e$, produces a negative feedback voltage which is in phase with the voltage e_o in the pass band due to the fact that the current $a_i e$ and the voltage e_o are substantially in phase when the tank circuit is near resonance. In those circuits where this in-phase component of internal feedback, in addition to the voltage e_f in quadrature therewith, is appreciable, the external feedback circuit of Fig. 6 is provided. Here, external capacitances C_1 and C_2 and a resistance R_2 are provided to make a balanced bridge. The neutralizing voltage e_n is now seen to be the vector sum of the voltages across the resistance R_2 and the condenser C_2 , the former neutralizing the component of feedback voltage in quadrature with the output voltage e_o and the latter neutralizing the component in phase therewith due to the resistance r_c . The conditions imposed on the external parameters are readily derived by equating e_n and e_f , assuming an applied voltage e_o . Reducing the equations and equating real and imaginary parts in the usual way, we find:

$$(3) \quad \frac{r'_b}{C_1} = \frac{R_2}{C_e}$$

and

$$(4) \quad \frac{r'_b}{C_1} = \frac{r_c}{C_2}$$

Equations 3 and 4 are based upon the equivalent circuit as shown in Fig. 5. If this circuit is changed by assuming the connection of an added resistance between the common connection of r_e and r_c and the common connection of C_e and r'_b , we then have the same circuit as that of Fig. 2 except for the addition of the resistance r_c . In this case, where the resistances r_b and r'_b are not assumed to be substantially equal, it is similarly found that the conditions for neutralization are

$$(5) \quad \frac{r'_b}{C_1} = \frac{R_2}{C_e}$$

and

$$(6) \quad \frac{r_b}{C_1} = \frac{r_c}{C_2}$$

where the values are such that

$$(7) \quad r_c \gg \frac{1}{\omega C_o} \gg r'_b$$

a condition that can readily be obtained with practical transistors.

Fig. 7 illustrates a conventional amplifier having a p-n-p junction transistor T_1 connected for a base input. Batteries E_3 and E_4 provide the usual base and collector bias. An inductance L and a capacitance C_o comprise a tuned tank circuit which, in the pass band, supply maximum power to an equivalent load resistance R_L through a transformer coupling. Again, as in the case of the emitter input connection of Fig. 1, the observed characteristics of the circuit reveal the presence of internal feedback, producing resistance and reactance characteristics like those of Fig. 12. The observed results are expressed by the equivalent circuit of Fig. 8, where-

from it is apparent that the output voltage e_o affects the current delivered by the generator through its influence on the current i_b . The value α is again the transfer current amplification factor of the transistor.

5 To neutralize the internal feedback in the circuit of Fig. 7 there is provided the circuit of Fig. 9. Here, external impedances C_n , C_3 , C_4 and R_n are provided to make a balanced bridge. In this circuit, the inductance L is divided into parts L_1 and L_2 and the point of connection of these parts is joined with the connection between the impedances R_n and C_3 . The values of the parameters are found in the following manner: First, assuming an applied input voltage e_o with the tap terminal on the inductance disconnected, no resultant voltage will 10 exist across the terminals of the input e_i if $e_n = e_i$ and $e_n = e_o$. These assumptions lead directly to the conditions

$$(8) \quad \frac{C_e}{C_3} = \frac{C_n}{C_4} = \frac{R_n}{r'_b}$$

20 The tap terminal connection is made at such a point on the inductance that the balanced condition is undisturbed. If

$$25 \quad r'_b \ll \frac{1}{\omega C_e}$$

this point is determined substantially by the expression

$$(9) \quad \left| \frac{V_1}{V_2} \right| = \frac{C_n}{C_e}$$

30 The circuit of Fig. 10 is the same as that of Fig. 9 except that the actual transistor connections are shown in place of the equivalent circuit.

It will be appreciated from the foregoing that by the 35 external feedback connections illustrated herein, it is possible to unilateralize partially or entirely junction-type transistor amplifiers having either base or emitter input connections, thereby achieving higher gains, greater stability and selectivity, and more nearly ideal input and 40 output impedance characteristics, especially for higher frequency applications. This permits the use of transistors in a variety of functions hitherto performed exclusively by the unilateral forms of vacuum tube circuits, notably the pentodes. Moreover, it will be further understood that, while various specific circuits and connections for neutralization and unilateralization are described herein for the purpose of illustrating the invention, such modifications of connections, circuits and 45 adjustments of parameter values therein as would occur to one skilled in the art upon a reading of the foregoing specification are within the spirit and scope of the invention.

50 Having thus described the invention, I claim:

1. An amplifier circuit having, in combination, a transistor having a collector and base and emitter electrodes, a circuit connecting the collector and base electrode of the transistor including an inductance in parallel with a branch circuit, said branch circuit including capacitance and resistance elements in series, said inductance and said 55 capacitance providing a resonant tuned circuit at frequencies in the pass band of the amplifier, output means inductively coupled with said inductance, and an input circuit connected between one of said electrodes and a point in said branch circuit between said capacitance and resistance elements, said elements in said branch circuit being arranged in combination with said input circuit to provide external inverse feedback to the transistor whereby the transistor is rendered substantially nonresponsive to its inherent internal feedback.
2. An amplifier circuit having, in combination, a transistor having a collector and base and emitter electrodes, a circuit connecting the collector and base electrode of the transistor including an inductance in parallel with a branch circuit, said branch circuit including capacitance 60 and resistance elements in series, said inductance and said 65 capacitance providing a resonant tuned circuit at frequencies in the pass band of the amplifier, output means inductively coupled with said inductance, and an input circuit connected between one of said electrodes and a point in said branch circuit between said capacitance and resistance elements, said elements in said branch circuit being arranged in combination with said input circuit to provide external inverse feedback to the transistor whereby the transistor is rendered substantially nonresponsive to its inherent internal feedback.
3. An amplifier circuit having, in combination, a transistor having a collector and base and emitter electrodes, a circuit connecting the collector and base electrode of the transistor including an inductance in parallel with a branch circuit, said branch circuit including capacitance 70 and resistance elements in series, said inductance and said 75 capacitance providing a resonant tuned circuit at frequencies in the pass band of the amplifier, output means inductively coupled with said inductance, and an input circuit connected between one of said electrodes and a point in said branch circuit between said capacitance and resistance elements, said elements in said branch circuit being arranged in combination with said input circuit to provide external inverse feedback to the transistor whereby the transistor is rendered substantially nonresponsive to its inherent internal feedback.

capacitance providing a resonant tuned circuit at frequencies in the pass band of the amplifier, output means responsive to the current circulating between the inductance and the branch circuit, and an input circuit connected between one of said electrodes and a point in said branch circuit between said capacitance and resistance elements, said elements in said branch circuit being arranged in combination with said input circuit to provide external inverse feedback to the transistor whereby the transistor is rendered substantially nonresponsive to its inherent feedback.

3. An amplifier circuit having, in combination, a transistor having a collector and base and emitter electrodes, a circuit connecting the collector and base electrode of the transistor including an inductance in parallel with a branch circuit, said branch circuit including, in series connection, a resistance element and a capacitance element interposed between said resistance element and the collector, said inductance and said capacitance providing a resonant tuned circuit at frequencies in the pass band of the amplifier, output means inductively coupled with said inductance, and an input circuit connected between the emitter electrode and a point in said branch circuit between said capacitance and resistance elements, said elements in said branch circuit being arranged in combination with said input circuit to provide external inverse feedback to the transistor whereby the transistor is rendered substantially non-responsive to its inherent internal feedback.

4. An amplifier circuit having, in combination, a transistor having a collector and base and emitter electrodes, a circuit connecting the collector and base electrode of the transistor including an inductance in parallel with a branch circuit, said branch circuit including capacitance and resistance elements in series, the inductance and capacitance being turned to resonate in the pass band of amplifier, output means inductively coupled with said inductance, and an input circuit between the emitter electrode and a point in said branch circuit between said capacitance and resistance elements, said elements in said branch circuit being arranged in combination with said input circuit to provide external inverse feedback to the transistor whereby the transistor is rendered substantially nonresponsive to its inherent internal feedback.

5. An amplifier circuit having, in combination, a transistor having a collector and base and emitter electrodes, a circuit connecting the collector and base electrode of the transistor including an inductance in parallel with a branch circuit, said branch circuit including first and second capacitance elements and a resistance element in series, said inductance and said capacitance providing a resonant tuned circuit at frequencies in the pass band of the amplifier, output means responsive to the current circulating between the inductance and the branch circuit, and an input circuit connected between one of said electrodes and a point in said branch circuit between said capacitance elements, said elements in said branch circuit being arranged in combination with said input circuit to provide external inverse feedback to the transistor whereby the transistor is rendered substantially non-responsive to its inherent internal feedback.

6. An amplifier circuit having, in combination, a transistor having a collector and base and emitter electrodes, a circuit connecting the collector and base electrode of the transistor including an inductance in parallel with a branch circuit, said branch circuit including first and second capacitance elements and a resistance element in series, the inductance and combined capacitance elements being tuned to resonate in the pass band of the amplifier, output means inductively coupled with said inductance, and an input circuit connected between one of said electrodes and a point in said branch circuit between said capacitance elements, said elements in said branch circuit being arranged in combination with said input circuit to provide external inverse feedback to the transistor whereby the transistor is rendered substantially nonresponsive to its inherent internal feedback.

7. An amplifier circuit having, in combination, a transistor having a collector and base and emitter electrodes, a tapped inductance element, a first capacitance element connected between one end of the inductance element and the tap and also between the emitter electrode and collector of the transistor, a resistance element and a second capacitance element series-connected between said tap and the other end of the inductance element, a third capacitance element connected between said other end and the base electrode of the transistor, an output circuit inductively coupled with said inductance, and an input circuit connected between the base electrode and the common connection between said resistance and second capacitance elements, said resistance and capacitance element being arranged in combination with said input circuit to provide external inverse feedback to the transistor whereby the transistor is rendered substantially non-responsive to its inherent internal feedback.

8. An amplifier circuit having, in combination, a transistor having a collector and base emitter electrodes, a tapped inductance element, a first capacitance element connected between one end of the inductance element and the tap and also between the emitter electrode and collector of the transistor, a resistance element and a second capacitance element series-connected between said tap and the other end of the inductance element, a third capacitance element connected between said other end and the base electrode of the transistor, output means responsive to the current circulating between the inductance and said first and second capacitance elements, and an input circuit connected between the base electrode and the common connection between said resistance and second capacitance elements, said resistance and capacitance elements being arranged in combination with said input circuit to provide external inverse feedback to the transistor whereby the transistor is rendered substantially non-responsive to its inherent internal feedback.
